UNITED STATES PATENT OFFICE.

DEWITT A. BRUNETT, OF MINNEAPOLIS, MINNESOTA.

HOT-AIR FURNACE.

Application filed January 30, 1922. Serial No. 532,891.

To all whom it may concern:

Be it known that I, DEWITT A. BRUNETT, a citizen of the United States, residing at Minneapolis, in the county of Hennepin and 5 State of Minnesota, have invented certain new and useful Improvements in Hot-Air Furnaces; and I do hereby declare the following to be a full, clear, and exact description of the invention, such as will enable 10 others skilled in the art to which it appertains to make and use the same.

This invention relates to a heating system, and particularly to such a system including an auxiliary device in connection with a 15 furnace. The structure herein disclosed is an improvement upon that disclosed and claimed in Patent No. 1,392,888, granted to me October 4th, 1921.

It is an object of this invention to provide 20 an auxiliary heating device comprising a secondary combustion chamber and to also provide a conduit leading from a point adjacent the bottom of said chamber and upwardly through the combustion chamber of 25 the furnace proper and from thence to a smoke pipe.

It is a further object of the invention to have the auxiliary heating device as a separate unit and to have the combustion chamber 30 therein connected to the combustion chamber of the furnace by a conduit and to provide a conduit leading from this conduit to the conduit above mentioned which leads from the secondary combustion chamber 35 through the combustion chamber of the furnace.

These and other objects and advantages of the invention will be fully set forth in the following description made in connection 40 with the accompanying drawings in which like reference characters refer to the same parts throughout the different views, and in which

Fig. 1 is a vertical central section through 45 the device;

Fig. 2 is a top plan view of the same, as seen in Fig. 1;

Fig. 3 is a horizontal section taken on the line 3—3 of Fig. 1, as indicated by the 50 arrows;

Fig. 4 is a fragmentary vertical section similar to the section shown in Fig. 1 showing the lower part of a modification; and

Fig. 5 is a similar vertical section showing the upper part of said modification. 55

Referring to the drawings, the device comprises a furnace comprising a fire pot 1, which communicates at its upper end with a combustion chamber formed by a casing 2. An ash pit 3 is shown below the fire pot 1 and suitable door structures 4 are provided for the fire pot and said ash pit. The chamber 2 is surrounded by a shell 5 spaced therefrom at the top and sides and extending downwardly to a point some distance below 60 the bottom of the ash pit 3. The casing 2 forms a combustion chamber of the furnace or the so-called primary combustion chamber, and is connected by a conduit 6 to a casing 7 of an auxiliary heating device, 65 which casing and chamber therein form the secondary combustion chamber. The casing 7 is, likewise, surrounded by a shell 8 spaced therefrom at the top and sides and extending downwardly below the bottom of the 70 same. It will be noted that the top and bottom of the casing 7 are substantially level with the top of casing 2 and the bottom of the ash pit, respectively. The adjacent portions of the casings 5 and 8 are connected 75 by walls 10 and these walls, together with the remote sides of the casings 5 and 8, extend therefrom, continue downwardly below the bottom of the ash pit 3 and casing 8 to provide a common base air chamber 9, the bottom of said walls being illustrated in Fig. 1 as resting upon the ground or floor. The vertical walls of the casings 5 and 8 between the walls 10 terminate at the bottom of the casing 7 and ash pit 3 and are connected by 80 horizontal portion 11.

A plurality of open-ended and preferably cylindrical conduits 12 extend a short distance into the base air chamber 9 and pass vertically upward about the fire box 1 and 95 ash pit 3 and through the combustion chamber 2, the upper ends terminating flush with the top of said casing. A plurality of similar open-ended tubes 13 extend a short distance below the casing 7 and pass upwardly 100 therethrough, terminating at their upper ends substantially flush with the top thereof. The space between the top of casing 2 and shell 5 is divided into a plurality of pockets by radially extending partitions 14. These 105 partitions extend from the outer wall of

shell 14 inwardly to the wall of a central casing 15 which extends downwardly into the primary combustion chamber or casing 2 being closed at its bottom end and having a conduit 15^a connected to one side thereof adjacent its bottom curving downwardly and passing through the bottom of casing 2 and terminating flush with the bottom of the tube or conduits 12. The radial partitions 14 form pockets between the top of casing 2 and shell 5 in which pockets is located one of the tubes 12 and the radial partitions 14 are extended downwardly between the sides of the casing 2 and 5 to a point substantially in line with the bottom of the ash pit 3. These partitions extend inwardly to the fire pot 1 and ash pit 3 and form, in effect, vertical passages passing from the base air chamber 9 upwardly around the casing 2 and into the pockets at the top of casing 2. The space between the top of casing 7 and shell 8 is, likewise, divided into pockets by radial partitions 16 which pass inwardly from the wall of shell 8 to the wall of a central conduit 17 extending upwardly from the top of casing 7 and surrounding the upper end of a central tube 13. These radial partitions 16 form pockets with which one of the tubes 13 communicates and the partitions 16 are carried down to the bottom of casing 7, thus forming a series of vertical passages extending upwardly from the base air chamber 9 around the sides of the casing 7.

35 A fresh air supply conduit 18 communicates with the front of the base air chamber 9. Vertically extending conduits 19 communicate with the top of shell 8 and the pockets formed therein and are arranged to deliver the heat to the rooms or parts of the building to be heated. The central one of the conduits 19 is connected to the chamber 15. A plurality of similar conduits 20 communicate and connect with the top of shell 8 and with the pockets formed at the top thereof and are, likewise, designed, together with the conduit 17, to deliver the heat to the rooms or part of the building to be heated.

50 The chamber 7 has, adjacent its top, opposite to the side where conduit 6 connects, a smoke pipe connection 21, provided adjacent the casing 7 with a damper 22. The casing 7 is also provided adjacent its bottom and preferably on the same side as the conduit 6, with another conduit 23 which extends horizontally toward shell 5, passes into the same and then extends upwardly through the combustion chamber 2 through one of the pockets between partitions 14 and out the top of shell 5 where it again extends horizontally and communicates with the smoke pipe conduit 21. Another conduit 24 extends vertically from the top of conduit 6 and communicates with the conduit 23.

Conduit 23 is provided adjacent the casing 7 with a damper 25 and the conduit 24 is provided some distance below the upper conduit 22 with a damper 26. It will be seen that in the described structure, the conduit 23 replaces one of the tubes 12.

In the operation of the furnace the products of combustion from the fire box 1 pass into the combustion chamber 2 and are here partly consumed. The products of combustion then pass through the conduit 6 into casing 7 or the secondary combustion chamber where the combustion thereof is rendered complete. The air passes into the base air chamber 9 and upwardly through the tubes 12, is heated and delivered into the pockets at the top of the casing 2. Air, likewise, travels through the vertical passage between the partition 14 around the ash pit 3, fire box 1, combustion chamber 2 and is delivered into the pockets above casing 2. This heated air is then delivered from these pockets into the conduits 19 through which it passes to the rooms to be heated. Cold air, likewise, passes upwardly through the conduits 13 and is heated by the products of combustion in the secondary combustion chamber 7 and is delivered into the pockets between the partition 16 of the top of the casing 7, the central conduit 13 delivering into the central conduit 17. This heated air is then delivered through the conduit 17 and to conduit 20 to the rooms to be heated. Air also passes upwardly around the casing 7, and is heated.

With this structure, practically all of the heat is absorbed and used. As is well known, it is necessary to have the gases passing up the chimney somewhat heated in order to create the proper draft in the furnace. When the fire is first started, either the damper 26 or the damper 22 will be opened and the damper 25 closed. The products of combustion can then pass quickly to the smoke pipe and will not have to take the long course through the auxiliary heating device including the chamber 7. After the fire is well started, the dampers 26 and 22 will be closed and the damper 25 opened so that the products of combustion must then pass through the secondary combustion chamber 7 of the auxiliary heating device. In my former patent, a conduit was provided leading directly from the bottom of casing 7 to the smoke pipe. With this structure a certain degree of heat must be left in the gases passing through the auxiliary heater or the casing 7 in order to insure a sufficient draft.

With the structure above described, using the conduit 23, the circulation can be so arranged in the auxiliary heater that practically all available heat will be extracted from the gases or products of combustion. These products then, as they pass out and

up through the conduit 23 will be heated by the heat from the primary combustion chamber and raised to a sufficient temperature to give the desired draft in the smoke pipe. It 5 has been found that by this structure, a better control of the heat can be attained. The draft can also be nicely regulated when starting the fire by means of the conduit 24 with the damper therein. It will, of course, 10 also be understood that the various dampers shown can be opened to various degrees to control the circulation as desired.

In the modification shown in Figs. 4 and 15 5, instead of using the space of one of the conduits 12 for the conduit 23, the tube 12^a corresponding to one of the tubes 12 is used and the conduit 23^a is connected to the casing 7 and passes into and upwardly through the tube 12^a and then upwardly through the 20 pocket at the top of the casing 2 and into tube 19^a corresponding to a tube 19. The conduit 23^a then passes laterally out of conduit 19^a and is connected to the smoke pipe. The pipe 24 is provided as before described. 25 From the above description it will be seen that applicant has provided a novel form of furnace and one functioning in a novel way.

It will, of course, be understood that 30 various changes may be made in the form, details and arrangement of the parts without departing from the scope of applicant's invention which, generally stated, consists in the matter shown and described and set forth 35 in the appended claims.

What is claimed is:

1. A heating system comprising a furnace including a fire pot, a combustion chamber, an auxiliary heating device connected to said 40 combustion chamber, and a conduit leading from adjacent the bottom of said auxiliary heating device extending through the said combustion chamber of the furnace and connected with a smoke pipe.

45 2. A heating system comprising a furnace including a fire pot and combustion chamber, an auxiliary heating device comprising a casing forming a secondary combustion chamber, and a conduit leading from adjacent the bottom of said secondary combustion chamber and arranged to extend upwardly through the combustion chamber of the furnace and adapted to be then connected to a smoke stack.

50 55 3. A heating system comprising a furnace including a fire pot and combustion chamber, an auxiliary heating device separated from said furnace and including a casing forming a secondary combustion chamber, a 60 conduit connecting said secondary combustion chamber to the combustion chamber of said furnace, a conduit leading from adjacent the bottom of said secondary combustion chamber and arranged to pass upwardly through the combustion chamber of the furnace and

said furnace and then arranged to be connected to a smoke pipe, and a conduit connecting the first mentioned conduit and the second mentioned conduit.

4. A heating system comprising a furnace 70 including a fire pot and combustion chamber communicating therewith, a casing surrounding said first mentioned combustion chamber and spaced therefrom at the side and top, an auxiliary heating device separate from said furnace and comprising a casing forming a secondary combustion chamber, a shell surrounding the same and spaced therefrom at the sides and top, a common base air chamber extending beneath said 80 combustion chambers, a plurality of open ended tubes extending from the common base air chamber through the combustion chamber of the furnace and opening into the space between the same and the top of the 85 casing surrounding the same, a plurality of open ended tubes extending from the base air chamber through the secondary combustion chamber, and communicating with the space between the top of the same and to 90 said shell, a conduit connecting the combustion chamber of the furnace to the secondary combustion chamber, a plurality of conduits extending from the space above the first mentioned combustion chamber adapted to 95 carry the heat to the rooms to be heated, a plurality of conduits extending from the space at the top of the secondary combustion chamber and adapted to carry heat to the rooms to be heated, a conduit connected adjacent the bottom of the secondary combustion chamber extending horizontally through the shell and into the casing surrounding the combustion chamber of the furnace and upwardly through the latter and the space 105 at the top thereof, out through the top of the casing surrounding the same and then extending horizontally and adapted to be connected to a smoke pipe.

5. The structure set forth in claim 4, and 110 a conduit connected to the conduit which connects the said combustion chambers and extending to the last mentioned conduit having a damper therein, and a damper in the conduit extending from the bottom of the 115 secondary combustion chamber.

6. A heating system comprising a furnace including a fire pot and a combustion chamber communicating therewith, an auxiliary heating device having a casing therein forming a secondary combustion chamber, a conduit connecting the combustion chamber of the furnace and said secondary combustion chamber, a conduit extending from adjacent the top of the secondary combustion chamber adapted to be connected to the smoke pipe, a conduit extending from adjacent the bottom of the secondary combustion chamber and arranged to pass upwardly through the combustion chamber of the furnace and 120 125 130

then extending horizontally and communicating with the conduit adapted to be connected to the smoke stack and another conduit extending upwardly from the conduit connecting the two combustion chambers and communicating with the upper portion of the conduit extending from adjacent the bottom of the secondary combustion chamber.

7. The structure set forth in claim 1, and means for admitting gas from said combustion chamber into said conduit.

8. The structure set forth in claim 1, and a damper controlled passage for admitting gas from said combustion chamber into said conduit.

In testimony whereof I affix my signature.

DEWITT A. BRUNETT.
